A. F. JENKINS

ACETYLENE GENERATOR

Filed Dec. 27, 1919

A. F. Jenkins

By Foster, Freeman, Watson & Scott

Chamney

UNITED STATES PATENT OFFICE.

ALEXANDER F. JENKINS, OF BALTIMORE, MARYLAND.

ACETYLENE GENERATOR.

Application filed December 27, 1919. Serial No. 347,719.

To all whom it may concern:

Be it known that I, ALEXANDER F. JENKINS, a citizen of the United States, and residing at Baltimore city, State of Maryland, have invented certain new and useful Improvements in Acetylene Generators, of which the following is a specification.

The general object of this invention is to provide an improved acetylene generator, that is, an improved gas generating apparatus in which calcium carbide is treated with water to produce acetylene gas for lighting or other purposes. The invention relates particularly to generators which are designed and constructed to evolve large quantities of gas, such as are often employed to generate the gas used in lighting buildings and for oxyacetylene welding and cutting purposes.

One particular purpose of the invention is to provide an apparatus which is as nearly as possible automatic in operation, including automatic water and carbide feeding devices and means for the automatic removal of sludge. Another purpose of the invention is to provide an apparatus which is considerably smaller than similar devices of equal gas generating capacity heretofore designed or suggested, thereby increasing its portability and rendering it suitable for installation in convenient places from which these devices have in the past, by reason of their large size, been barred. This decrease in size is accomplished in the main by supplying to the generating chamber only a sufficient amount of water to react with the carbide. The water is drawn from a source of supply, such as a city main, through a pipe, and the usual large capacity water tank or reservoir is dispensed with. The carbide and water are fed in proportionate amounts and, as means is provided for removing the sludge and waste water, water is present in the chamber only in such volume as is necessary for efficiently reacting with the carbide.

One embodiment of the invention will be described in the following specification in connection with the accompanying drawings in which:

Figure 1 is a central longitudinal section through the gas generating apparatus; and

Figure 2 is a similar section taken at right angles to the section shown in Figure 1.

The apparatus illustrated comprises an elongated tank arranged in an upright position, the interior of the tank serving as the gas generating chamber and containing the mechanism for combining in proper proportions the carbide and water. As shown in the drawings, the cylindrical tank 10, preferably of sheet metal, has a head 11 and two separate and distinct bottoms 12 and 13, which are conveniently cone shaped, and which have orifices 14 and 15 at their lowest points. The head 11 is provided with an opening through which carbide is inserted into the tank the opening being normally closed by the removable screw plug 16. An additional opening is also provided in the head through which a water pipe 17 connected to any suitable source of supply passes, the water pipe extending for a considerable distance toward the bottom of the generating chamber and having a downwardly directed delivery orifice.

This water supply pipe 17 passes through the carbide hopper 18 which, as shown, is also substantially conical in shape, its upper edges being secured to the wall of the tank and a slot or orifice 19 being provided at its lowermost point through which the carbide is adapted to pass, in the operation of the generator.

Extending transversely across the generating chamber is a horizontally arranged rotatable shaft 20, the axis of the shaft being directly below and parallel with the edges of the orifice 19. Upon this shaft are fixed the water wheel 21 which is directly below the discharge orifice of the water supply pipe 17, the carbide feeding drum or cylinder 22 which is disposed beneath the orifice 19 and is of such diameter that its uppermost surface is close to and immediately below the carbide orifice 19, and the toothed wheel 23 positioned between the feeding drum and the water wheel. This arrangement is such, as can be readily seen from Figure 2, that when water issues from the supply pipe 17 and impinges on the vanes of the water wheel, the latter will be rotated, thereby causing the rotation of the shaft 20 and the rotation of the feeding drum and the toothed wheel fixedly mounted thereon.

The construction of the carbide orifice 19 is such that when the feed drum or cylinder 22 is stationary a small amount of the carbide will issue therefrom and "pile up" on

the top of the feed drum in such a way as to prevent the further discharge of carbide through the orifice. However, if the feed is rotated in the direction of the arrow (Figure 2) it will be seen that the small quantity of carbide on the upper side of the feed drum will be thrown off and that, so long as this feed drum or cylinder is rotated, no further "piling up" of the carbide in front of the 10 orifice 19 will be possible and a continual supply of the carbide will be withdrawn from the hopper 18. In other words, this carbide feeding mechanism operates only when water is passing down the pipe 17 to 15 actuate the water wheel.

The water after passing over the water wheel 21 falls to the bottom of the tank where it is retained until a predetermined volume is collected, by a ball valve 24 which 20 normally seats in the orifice 14, and the movements of which are controlled by a float 25, of ordinary construction, which is connected thereto. It can be seen that no water 25 will pass through the orifice 14 unless the water level is raised to such a point that the float 25 will lift the valve 24 off of its seat and that the flow issuing will only endure so long as the float 25 maintains the ball valve 23 off of its seat. As a consequence there is 30 always a considerable quantity of water in the bottom of the generating chamber, and the water is always of such a depth that it completely submerges a wire screen 26 which is designed and constructed to catch the carbide which falls from above and to retain the same thereon until it has ceased to evolve gas and has become sludge. After the gas producing qualities of the carbide have been exhausted, it falls to the bottom of the generating chamber and, when the valve 24 has been raised, this sludge passes out with the excess water into the chamber below.

The orifice 15 in the bottom 13 of this lower chamber is controlled by a ball valve 27 connected to a float 28 so that there is 45 always a definite volume of water in this lower chamber; and when an excess of water intermingled with sludge is received therein from the generating chamber, the float 28 will raise the valve 27 from its seat and a corresponding volume of water will pass through the orifice 15 and into the waste pipe 29.

A service pipe 30 communicates with the 50 upper end of the generating chamber and through this pipe the gases generated are conducted away. To the top 11 of the tank is connected a diaphragm pressure responsive device 31 of well known type having a stem 32 which moves vertically in response to variations in the pressure of the gas contained in the tank. A lever 33 pivoted at 55 34 to a bracket rigidly connected to the member 31 connects the member 32 to the arm 35 of a valve 36 which controls the flow of

water through the water inlet pipe 17. The pressure responsive device 31 is so designed and the member 32 is so connected to the valve 36 that the latter will be opened to admit more water to the generating chamber 70 when the pressure therein has fallen below a predetermined amount or value and will close the valve whenever the pressure in the chamber is greater than this predetermined amount. 75

In order to prevent excessive generation of gas with consequent dangerous pressure in the tank and system due to some accident by which the amount of water supplied to the cylinder is too great, I provide a safety 80 locking device which locks the shaft 20 against rotation when the water level in the generating chamber has arisen above a predetermined point. This safety device is also designed to stop the feeding of carbide in 85 case the sludge valves should leak and not maintain the water at a proper level in the generating chamber. This safety locking device comprises a stop 37 pivotally connected at 38 to a bracket 39 fastened to the inner wall of the cylinder, one arm of the stop being pivotally connected by means of a rod 40 to a float 41. If the water level rises, due to the sticking of the valve 24, or any other accidental cause, the float 41 will move upwardly thereby forcing the upper end of the stop 37 into one of the notches of the toothed wheel 23 and preventing the rotation of the feed drum, and cutting off the supply of carbide. An additional arm 42 is provided 90 which operates to engage and lock against rotation, the wheel 23 when the water level in the generating chamber has fallen below the desired point. In other words, this locking mechanism will stop the operation of the 95 generator whenever the supply of water is too great or too small, but will automatically restore it to operative condition whenever the normal conditions are restored.

It will be seen from the above description 100 that I have provided a generator which is simple, compact and practically automatic in all respects. By removing the plug 16 in the top of the tank and connecting the carbide hopper 18 to one of larger size or one 105 which is continuously filled, the generator will operate for long periods of time inasmuch as the fresh water is supplied automatically and the used water and sludge is removed automatically. There is present in 110 the generating chamber of my gas generating device only a sufficient amount of water to efficiently react with the calcium carbide and the large reservoirs for water so commonly used in generators of this class is done 115 away with. The moving parts are simple and quite unlikely to become out of order; while the occurrence of excessive pressures in the tank and system is fully guarded 120 against by the provision of the safety lock 125 130

ing device for the carbide feed. No manual means is required to actuate the carbide feed, the water introduced for the purpose of moistening the carbide also performing the work of feeding the carbide, as it falls to the bottom of the chamber. A single pressure responsive device serves to regulate both the water and the carbide feed and, in general, the simplicity, compactness and safety of my improved generator, combined with its automatic features, renders it particularly attractive and advantageous from a practical standpoint.

It will be evident that certain features of the invention may be used independently of other features. Thus the sludge removing apparatus may be used with a non-automatic carbide feed or an automatic feed of a different character, such as one operated by clock-work. An independent water connection 50 is provided for occasionally washing out the generating chamber, and removing the sludge in case the apparatus should become clogged. By shutting off the water through pipe 17 and opening the valve 51 the carbide feed will stop and the sludge valves 24, 27, will open permitting a thorough washing of the lower part of the apparatus.

Having thus described the invention what is claimed as new and desired to secured by Letters Patent is:

1. In an acetylene generating apparatus, the combination with a generating tank, of means for feeding water and carbide thereto, including a rotary carbide feeding member, a water wheel operatively connected thereto, a feed water conduit having its orifice adjacent the water wheel whereby said wheel and the carbide feeding member are operated by the energy of the feed water entering the tank, and means responsive to the water level for locking the carbide feeding member against rotation when the level of the water in the tank rises above a predetermined point.

2. In a gas generating and storage tank, means for introducing water into the tank, means operated by said admission of water for admitting a proportionate amount of carbide, and means responsive to the water level for positively locking said carbide admitting means against movement, when the water in the tank is below a predetermined level.

3. In a unitary gas generating and storage tank, means for introducing water into the tank, means operated by the admission of water for feeding a proportionate amount

of carbide, and means responsive to the water level for positively preventing the admission of the carbide when the level of the water rises above a predetermined point.

4. In a unitary gas generating and storage tank, pressure responsive means for introducing water into the tank, a continuously rotatable carbide feeding drum operated by said admission of water, and means responsive to the level of the water in the tank for locking said drum against rotation.

5. In a unitary gas generating and storage tank, means for introducing water into the tank, a continuously rotatable member operated by the admission of the water and adapted to feed a proportionate quantity of carbide, and means responsive to the water level for positively locking said carbide feeding member against movement when the water level in the tank rises above a predetermined point or falls below a predetermined point.

6. In a gas generating apparatus, the combination with a generating chamber having an opening therein for the introduction of carbide and an opening for the removal of water and sludge, of means for introducing water into said chamber, automatic means for controlling said water introducing means whereby water is allowed to flow into the chamber when the gas pressure becomes lower than a predetermined value and prevented from entering the chamber when the gas pressure becomes higher than a predetermined value, automatic means for bringing fresh carbide into contact with water in the generating chamber when the gas pressure becomes lower than a predetermined value, said means being inoperative when the pressure becomes greater than a predetermined value, automatic means for controlling the flow of water and sludge from said chamber, and automatic means for locking the carbide controlling means against movement when an excess of water is present in said chamber.

7. In a unitary acetylene generator and storage tank, means for introducing water into the generating chamber, means comprising a continuously rotatable drum for automatically feeding the carbide to said chamber and a stop for the carbide feed, said stop being controlled by a float adapted to prevent the feeding of carbide when the water in the chamber is either above or below predetermined limits.

In testimony whereof I affix my signature.
ALEXANDER F. JENKINS.
